UNITED STATES PATENT OFFICE.

JOHN MCKINLEY AKERS AND WALTER CARL AKERS, OF MATEWAN, WEST VIRGINIA,
ASSIGNORS OF ONE-THIRD TO L. T. COMPTON, OF MATEWAN, WEST VIRGINIA.

PNEUMATIC SUPPORT FOR VEHICLE BODIES.

Application filed March 8, 1923. Serial No. 623,791.

To all whom it may concern:

Be it known that we, JOHN M. AKERS and WALTER C. AKERS, citizens of the United States, residing at Matewan, in the county 5 of Mingo and State of West Virginia, have invented certain new and useful Improvements in Pneumatic Supports for Vehicle Bodies; and we do declare the following to be a full, clear, and exact description of the 10 invention, such as will enable others skilled in the art to which it appertains to make and use the same.

Our invention has for one object to provide a simple yet an efficient pneumatic support for vehicle bodies, novel provision being made whereby both depressions and projections in the roadway will be prevented from seriously jarring the body.

In carrying out the above end, pistons 20 are movably mounted in a cylinder and their movement is controlled by check valved pressure inlets and outlets, a further aim being to provide a novel arrangement of parts, permitting the pressure to carry with it a 25 quantity of oil vapor, as it passes to the cylinder, thus effectively lubricating the pistons.

With the foregoing in view, the invention resides in the novel subject matter herein- 30 after described and claimed, the description being supplemented by the accompanying drawings.

Figures 1 and 2 are diagrammatic sectional views, partly in elevation, showing 35 the manner in which the device operates when the vehicle wheels strike a depression or a projection, respectively.

Figure 3 is an enlarged sectional view of 40 one of the cushioning devices.

In the drawings above briefly described, 45 the numeral 1 designates an elongated cylinder having a head 2 at one end and provided with a centrally apertured closure 3 at its opposite end. A floating piston 4 is 50 slidable in the portion of the cylinder adjacent the head 2 and has limited inward movement away from said head, from which it is normally spaced as shown in Figs. 1 and 3. To so limit the inward movement of 55 the piston 4, we preferably enlarge one end of the cylinder as indicated at 5, forming an

internal shoulder 6 at the junction of its two diameters, said piston having an enlarged head 7 sliding within the cylinder enlargement and adapted to strike the shoulder 6 to limit the inward movement of said piston. At times, the piston 4 moves toward the cylinder head 2, in which instance atmospheric air is admitted into the portion 55 of the cylinder between its normal and enlarged diameters, a check valved air inlet 8 being provided for this purpose. The air which enters through the passage 8 may escape slowly through a bleed port 9 which, in the construction disclosed, is in the wall 60 of said passage.

A pipe 10 having an outwardly closing check valve 11 leads to the cylinder 1, adjacent its head 2 and in the construction shown, this pipe extends from an oil containing casing 12 at the exterior of said cylinder. A pressure supply pipe 13, having a suitable control valve 14 leads to the casing 12 and receives air pressure or other fluid pressure from a supply tank 15 suitably carried by the body of the vehicle or by the chassis frame thereof, if the vehicle is in the form of an automobile. In the construction shown, the pipe 13 communicates with another pressure supply pipe 16 and the latter extends from the tank 15, but this exact piping is not absolutely essential. The pipe 13 depends into the oil casing 12 to a point below the oil level, while the inlet end of the pipe line 10 is above the oil level. It 70 will thus be seen that by filling the casing 12 with lubricating oil to the desired extent, that any pressure passing through the pipe 13 and out of the pipe 10 into the cylinder, will necessarily travel through the oil, thus 75 causing it to pick up a quantity of oil vapor and conduct it to said cylinder, for the purpose of lubricating the piston 4.

Slidable within the cylinder 1, between the closure 3 and the piston 4, is a second 80 piston 17 having an operating rod 18 extending through said closure and adapted for connection with the axle of the vehicle in any desired manner. In the present disclosure of our invention, we have pivoted 85 the lower end of the rod 18 to a lever 19 which is connected at one end to the axle 20

and is fulcrumed at its other end to a suitable part 21 which may well be carried by the body or chassis frame 22, to which the cylinder 1 is also connected. A pressure supply pipe 23 enters the cylinder between the two pistons 4 and 17 and is provided with an outwardly closing check valve 23', said pipe 23 leading from an oil containing casing 24 into which the pipe 16 extends, said 10 casing having the same function as the casing 12 above described. A pressure outlet pipe 25 having an outwardly opening check valve 26 leads from the cylinder 1 to the pipe 16 and is normally closed by the piston 17, and another pressure outlet pipe 27 having an outwardly opening check valve 28, leads from the enlarged portion 5 of the cylinder 1 to the pipe 18, in the present disclosure. These pipes 25 and 27 however 20 might otherwise be connected with the pressure tank 15, if desired.

By the construction shown, when a wheel of the vehicle comes over a depression in the roadway, pressure from the tank 15 25 enters the cylinder between the two pistons 4 and 17, forcing the latter downwardly, although the piston 4 does not then move upwardly under the influence of this pressure, due to the enlarged area of its upper 30 end and the pressure supplied between said end and the cylinder head 2. When the axle again moves upwardly, the pressure is forced from the cylinder through the valved outlet pipe 25 and returns to the tank 15, 35 and it will be seen that this operation will raise the piston 4 to some extent, during which movement, atmospheric air will enter through the check valved passage 8. Attention may be directed to the fact that as 40 soon as the piston 17 closes the outlet pipe 25, a quantity of compressed air is trapped between the two pistons, so that piston 17 cannot strike the piston 4. This trapped air may gradually leak out, for instance 45 through some of the joints 29 in the piston rings 30, which are used on the piston. At the same time, the air which enters under the piston head 7 when the latter moves upwardly, leaks slowly out of the bleed 50 port 9 and the piston 4 returns to its normal position, permitting it to gradually come into contact with the piston 17.

We will now assume that the wheels encounter a projection in the roadway and 55 that the axle 20 rises as diagrammatically illustrated in Fig. 2. Under this occurrence, both pistons 17 and 4 move bodily upward as a single unit and the air within the upper end of the cylinder is forced out of the pressure outlet pipe 27, effectively absorbing the shock. If this shock is extremely severe and the piston 4 moves upwardly beyond the pipe 27, the head of said piston is prevented from striking the cylinder head 2, 60 by the air cushion which is formed in the

cylinder as soon as the piston cuts off the outlet of air through said pipe 27. While the piston 17 may now return quickly to its initial position, piston 4 will again lower slowly and the air beneath its head leaks 70 out through the bleed port 9. Thus, this piston may again come in contact gently with the piston 17. It will be observed that each time one of the pistons moves in a manner to cause pressure from the tank 15 75 to enter the cylinder, this pressure will carry with it a quantity of oil vapor to effectively lubricate the internal working parts.

As excellent results are obtainable from the details disclosed, these details may be 80 followed if desired. However, it is to be understood that the present disclosure is for illustrative purposes only and that within the scope of the invention as claimed, numerous changes may be made. 85

We claim:

1. A cushioning device comprising a cylinder, a pair of relatively movable pistons in said cylinder movable one by means of the other, and check valved pressure inlets and outlets for said cylinder to control the movement of said pistons. 90

2. A cushioning device comprising a cylinder, a floating piston therein, movable toward and from the cylinder head, means for limiting the inward movement of said floating piston away from the cylinder head, a check valved pressure inlet passage for the cylinder between its normal inward position and the cylinder head, a pressure tank from which said pressure inlet passage leads, and a check valved pressure outlet passage leading from the cylinder at a point adjacent said inlet passage and discharging into said tank; a second piston in the cylinder between said floating piston and the other end of the cylinder, said second piston having an operating member extending to the exterior of the cylinder, a check valved pressure inlet passage from said tank into the cylinder between the two pistons, and a check valved pressure outlet passage from the cylinder normally covered by said second piston and discharging into said tank, said second named piston being movable inwardly into contact with said floating piston to operate the latter. 100

3. A structure as specified in claim 2; said cylinder being enlarged adjacent its head and having a check valved atmospheric air inlet and a bleed port at the junction of its two diameters, said floating piston having an enlarged head in the cylinder enlargement; said enlarged piston head and the shoulder formed by the cylinder enlargement, forming said means for limiting the inward movement of said floating piston. 120

4. A structure as specified in claim 1; each of said pressure inlets including a container for lubricating oil through which the pres- 125 130

sure passes whereby to carry oil vapor to the cylinder.

5. The combination with a containing member for a pressure operated part; of an oil containing casing at the exterior of said member, a pressure supply pipe entering said casing and extending below the oil

level, and a pressure passage leading to said member from said casing at a point above the oil level.

In testimony whereof we have hereunto affixed our signatures.

JOHN MCKINLEY AKERS.
WALTER CARL AKERS.
